CARGO HOIST

Nils Peter Erik Andersen, Elm Grove, Wis., assignor to Harnischfeger Corporation, Milwaukee, Wis., a corporation of Wisconsin

Application October 9, 1944, Serial No. 557,873

2 Claims. (Cl. 214—15)

1

This invention relates to hoists associated with ships for lifting cargo from alongside the ship to within the hold or from the hold to alongside the ship, and it resides more specifically in a novel combination with a ship of a transverse, overhead girder, extensible beyond the side of the vessel having a hoisting trolley movable lengthwise thereof, the whole being capable of movement fore and aft of the vessel and capable of being lowered from over head position to a stowed position of lowered center of gravity when not in use.

The problem of lifting cargo into and out of a ship has heretofore been dealt with in conventional fashion by derricks formed of mast and booms rigged in pairs to hoist, "telegraph" and lower the load. A minimum of two highly skilled winch operators and several signal men is required to safely operate such a rigging and the rate of handling is quite restricted. More effective means for performing this task have been proposed from time to time but all of these arrangements have been open to objection upon various grounds. For speedy, precise and safe handling of the cargo, overhead traveling bridge cranes have many advantages but they are expensive and the large exposed overhead runways entail an awkward disposition of weight, offer a large amount of windage surface, and when extended over the side of the vessel preempt a considerable space which may not be available because of existing dock structures. Means by which the heavy bridge of such cranes can be lowered to the deck to reduce the exposure thereof while at sea and to improve the disposition of weight have been proposed and constructed and such means have served to eliminate part of the disadvantages of such structures, but this has increased rather than decreased the cost thereof. The principle of hoisting the load and then moving it over a track transversely of the vessel and across the ship's rail and then lowering it by means carried by the ship itself has not heretofore been embodied in any apparatus which has not suffered at least some of the disadvantages above mentioned.

The apparatus of this invention, however, avails of the speed, safety and precision of the principle of horizontal movement on a track and of hoisting and lowering therefrom, while at the same time it dispenses entirely with any structure which need remain aloft while the ship is at sea and further it preempts no dock space beyond the side of the vessel any wider than the load being handled. The apparatus exhibits the additional advantage of mobility permitting its movement

fore and aft for utilization above a plurality of hatches ranged lengthwise of the ship. The apparatus furthermore may be readily operated to lift or lower on either side of the vessel and all of its motions may be conveniently controlled from positions permitting full observation of the load being handled.

This invention is herein more particularly described by reference to the accompanying drawings forming a part hereof and in which there is set forth by way of illustration and not of limitation one specific form in which this invention may be embodied.

In the drawings:

15 Fig. 1 is a sectional view in end elevation of one form of a ship and hoist of this invention.

Fig. 2 is a side view in elevation of the hoisting apparatus appearing in Fig. 1 when in erected operating position.

20 Fig. 3 is a side view in elevation of the hoisting apparatus appearing in Fig. 2 when in non-operating lowered position.

Fig. 4 is a detailed view in side elevation with parts broken away showing one of the self-propelled traveling shear leg feet upon which the hoisting apparatus is mounted.

Fig. 5 is a detailed view in end elevation and in section of the foot depicted in Fig. 4 viewed thru the plane 5—5 there indicated.

30 Fig. 6 is a detailed view in side elevation and in section of the main supporting girder, shiftable trolley way and associated parts shown in Fig. 1 viewed thru the plane 6—6 there indicated.

Fig. 7 is a diagrammatic skeleton showing in perspective of the reeving of the line systems by which hoisting of the load and traversing of the trolley is accomplished.

Fig. 8 is a diagrammatic skeleton showing in perspective of the racking chain layout and propelling circuits by which the self-propelled shear leg feet of the hoisting apparatus are moved to erect, lower and shift the hoisting apparatus fore and aft.

In the apparatus shown in the drawings, a ship 1 having hatches 2 is provided with parallel fore and aft runways 3 secured on opposite sides of a deck 4 between hatches 2 and the ship's rails 5 as appears more clearly in Fig. 1. The runways 3 are capped by rails 6 which are flanked on either side by free chains 7, shown in more detail in Figs. 4 and 5, the same being anchored fore and aft in a manner to be more fully described. Mounted for movement along each of the runways 3 upon the rails 6 are a pair of trucks 8.

The trucks 8 are shown more in detail in Figs.

4 and 5 and are made up of transversely joined side frame members 9 which support axles 10 and 11 upon which truck wheels 13 and 14 are mounted. On both sides of the truck wheels 14 between the same and the side members 9 are mounted freely-turning guide sprockets 15. Each truck 8 is also provided with a transverse driving shaft 16 carrying two driving sprockets 17 disposed in alinement with guiding sprockets 15. Also mounted upon shaft 16 between said driving sprocket 17 and secured thereto in driving relationship therewith is a sprocket engaged by a transmission chain 18. Transmission chain 18 is in turn in engagement with a sprocket mounted upon the output shaft 19 of a motor 20. Beyond the driving sprockets 17 and in alinement therewith is a pair of freely turning idler sprockets 21 which are mounted upon a cross shaft 22 carried by the side frame members 9.

Chains 7 as shown more clearly in Fig. 8 are secured at the ends of the runways 3, one end of the attached being by means of equalizer sheaves 23 and the other end by means of turn buckles 18 diagrammatically depicted. By reason of this arrangement, when motor 20 is operated and sprockets 17 are driven thereby, the truck 8 is propelled along the runway 3 in a positive fashion in much the same fashion as tho a driven pinion on the truck engaged a stationary rack associated with the runway. The chain 7, however, is preferred to a rack, since accidental damage to it can be easily repaired by replacement of the damaged links, and further it is less likely to be damaged because it may be displaced by an accidental blow which would not deform the same but which would deform a rigidly placed rack. If desired, the rack and pinion arrangements could of course be employed to accomplish the purpose intended.

The trucks 8 are mounted in pairs upon the runways 3 and one pair of such trucks is pivotally secured to and supports a pair of sheer legs 24. The other pair of trucks 8 is pivotally secured to and supports the pair of sheer legs 25. The pair of sheer legs 24 as appears more clearly in Figs. 2 and 3 is pivotally joined at its top by a pivot pin 26 which is of considerable horizontal extent. In like manner, the pair of sheer legs 25 is pivotally joined at its top by a similar pin not shown.

Extending between the sheer legs 24 and sheer legs 25 is a transverse girder 27 which is pendently attached to the pivot pin 26 by the brackets 28 on the one hand and similarly secured on the other hand by brackets, not shown, to the pivot pin connecting the upper ends of sheer legs 25. By reason of the substantial lateral extent of the pivot pins joining the tops of the sheer legs and engaging the brackets secured to the girder 27 the sheer legs 24 and 25 are restrained against a tipping tendency.

The pair of trucks 8 secured to sheer-legs 24, when moved toward one another cause the upper pivoted end of sheer-legs 24 to rise and to carry the end of the girder 27 secured thereto upwardly also. In like manner, when the pair of trucks 8 secured to the sheer-legs 25 are moved toward one another, the opposite end of the girder 27 is raised. Since the object is to always preserve the girder 27 in a horizontal position, the trucks 8 are arranged to be moved in unison. One method of accomplishing movement of the trucks 8 in unison is diagrammatically illustrated in Fig. 8 where the motors 20 opposite one another are shown with their armatures in series but

with the field of one shunted across the armature of the other and vice versa.

As shown more clearly in Figs. 2 and 3, the sheer legs 24 when in raised operating position 5 are joined by a connecting link 29. In like manner but not shown, the trucks 8 attached to sheer-legs 25 are also joined by a connecting link when in upper raised position. When in this position, if desired, all four of the trucks 8 may be translated simultaneously in the same direction to move the entire structure fore and aft over the deck of the vessel so that all hatches within the scope of the runway 3 may be accessible. As appears in Fig. 3, when sheer legs 24 and 25 are in lowered position, the trucks 8 may be also joined by a substitute link 30 which permits the structure to be maneuvered as a unit in lowered position and which also relieves the chains 7 of stress when the structure is in lowered position and not in use.

Extending downwardly from the sides of the girder 27 is a series of roller brackets 31 which appear in greater detail in Fig. 6. Secured to the lower ends of the brackets 31 are freely rotatable vertical rollers 32 and freely rotatable horizontal rollers 33. Mounted upon and in engagement with the rollers 33 is an end-wise translatable trolley-way bearing the general designation 34. The trolley-way 34 as appears more clearly in Fig. 6 is provided on each side with a pair of vertical acting rails 35 spaced apart a slightly greater distance than the diameter of the guide wheels 32. At the extreme lower outer edges of the trolley-way 34 are horizontally acting rolling surfaces 36 disposed to cooperatively engage the rollers 33. In this way the brackets 31 secured to the girder 27 serve to support the trolley-way 34 for translatory movement from the position shown in full lines in Fig. 1, overhanging the side of the vessel on one side to the position shown in dot and dash lines to the right thereof overhanging the opposite side of the ship 1.

The trolley-way 34 is formed so as to present 45 a downwardly-opening slot throughout its entire length, the margins of which slot are framed by upwardly-facing rails 37. Mounted to travel upon the rails 37 is a trolley bearing the general designation 38 made up of a frame 39 and trolley 50 wheels 40. The trolley 38 is thus adapted for movement along rails 37 lengthwise of the trolley-way 34.

For causing and controlling the movement of trolley-way 34, a rack 41 is mounted thereon in 55 meshing engagement with a gear 42 rotatably carried by a shaft centrally disposed with respect to girder 27. Gear 42 meshes in driven relationship with a pinion 43 mounted upon rotatable shaft 44 which in turn carries a transmission gear 45. Transmission gear 45 is engaged in turn by transmission gear 46 adapted to be driven by motor 47 shown diagrammatically only in Fig. 1. Upon turning of gear 42 which engages rack 41, trolley-way 34 is translated in accordance with 60 the direction of turning of said gear 42. To bring about movement of trolley 38 independently of position of or movement of trolley-way 34, a cable 48 is provided. The cable 48 is diagrammatically depicted by dotted lines in Fig. 7 where it appears that one end thereof wrapped about drum 49 passes first to a sheave 50 which is secured within the girder 27. From sheave 50 the cable 48 passes between the girder 27 and the trolley-way 34 to a freely-rotatable sheave 51 mounted upon the right hand end of the trolley.

way 34. Sheave 51 is hidden in the several figures of the drawing and appears only in the diagrammatic showing set forth in Fig. 7. From the sheave 51 the cable 48 passes to an attachment with the frame 39 of the trolley 38.

Also wrapped about the drum 49 but in direction opposite to that of cable 48 is a cable 52 which passes first to a sheave 53 mounted adjacent to sheave 50. From sheave 53 cable 52 passes to a freely-rotatable sheave 54 mounted upon the left hand end of the trolley-way 34. From the sheave 54 the cable 52 passes to a connection with the adjacent side of the frame 39 of the trolley 38. From this it will appear that upon rotation of drum 49 trolley 38 will be caused to roll upon its wheels 40 endwise with respect to trolley-way 34. At the same time, the trolley-way 34 may itself be translated and if the drum 49 is stationary the trolley 38 will remain stationary in spite of the movement of the trolley-way 34. If the drum 49 be rotating during such movement of the trolley-way 34 the movement of the trolley 38 will be dependent only upon the rotation of drum 49 and will be independent of the movement of trolley-way 34. Drum 49 is mounted to be rotatably driven by transmission gearing 55 and motor 56 mounted upon girder 27 and shown diagrammatically only in Fig. 1.

Trolley 38 is provided with downwardly-extending hoisting means in the form of a cable 57 which passes over a double sheave lifting block 58. As appears more clearly in Fig. 7, both ends of cable 57 are secured to and wrapped about a drum 59 mounted upon the girder 27 and adapted to be rotatably driven by transmission gearing 60 and motor 61 diagrammatically shown in Fig. 1. One end of the cable 57 passes first to a sheave 62 carried upon the same shaft as that which supports the gear 42 at the center of girder 27. From the sheave 62 the cable 57 shown in full lines then passes to a sheave 63 mounted upon the left end of trolley-way 34. From the sheave 63 the cable 57 passes to a sheave 64 carried upon the frame 39 of the trolley 38. From the sheave 64 the cable 57 passes about one of the sheaves of the lifting block 58 and thence back to a sheave 65 also mounted upon the trolley 38. From the sheave 65 the cable 57 then passes to a sheave 66 mounted upon the right hand end of trolley-way 34, and after passing about the sheave 66 returns to sheave 67 carried upon the same shaft as sheave 62. The cable 57 continues thence around an equalizer sheave 68 anchored within the girder 27 and from said equalizer sheave passes to and around a sheave 69 also carried upon the same shaft as the one which supports sheave 62. From the sheave 69 the cable 57 then extends to a sheave 70 carried upon the right hand end of the trolley-way 34 and from the sheave 70 extends to and around sheave 71 mounted upon the trolley 38, the other sheave contained within the lifting block 58 and a sheave 72 mounted upon the trolley 38. From the sheave 72 cable 57 then passes around a sheave 73 carried at the left hand end of trolley-way 34 and from sheave 73 extends around sheave 74 mounted at the center of girder 27 and from thence back to drum 59.

From inspection of the reeving of cable 57 as depicted and as above described, it will be ascertained that vertical movement of lifting block 58 may be caused and controlled by rotation of drum 59 and that said vertical movement is independent of horizontal translation of the trolley-way 34 and the trolley 38 or either of them.

Control of motors 61, 41, 56 and 20 may be accomplished by switching means of conventional form and therefor not shown, regulated by a multiple push button pendant 75 conventionally attached and suspended as shown in Fig. 1.

It is intended that the apparatus above described when not in use, and while the ship 1 is at sea, shall be disposed in lowered position indicated in dot and dash lines in Fig. 1, in which position the apparatus as viewed from the side is as appears in Fig. 3. While in said lowered position, in order to relieve the load upon the link 30 and the trucks 8, jacks 76 shown in dotted lines in Fig. 3 and extended upwardly from the runways 3 may be provided. In this position the apparatus of this invention occupies a favorable position with regard to disposition of weight upon the vessel and a position in which windage is substantially reduced and exposure of the operating mechanism of the apparatus is minimized. Visibility is also little impaired by the apparatus of this invention when in said lowered position. When it is desired to place the apparatus in use, the trucks 8 are simultaneously brought together to raise the apparatus to the position shown in full lines in Fig. 1 and in Fig. 2. In performing this operation, if desired, supplementary tackle for bringing the trucks 8 together in unison may be resorted to, if desired such tackle serving the purpose of the two temporary links 29 and 30.

With the apparatus raised to operating position a load 11 may be lifted to and from a position within the hold of the ship 1 and a position beyond the side of the ship 1. For this purpose the trolley-way 34 is extended for example as shown in Fig. 1. The lifting block 58 is then lowered to engage the load and the load then lifted to a level at which it will clear the structures associated with the deck 4. The lifting of the load is then followed by movement of the trolley 38 under the influence of the motor 56 until the load is above the position in which it is to be deposited, whereupon the lifting block 58 is again lowered by paying out cable 57 from drum 59. If it is desired to lift a load from one side of the ship 1 to the opposite side, translation of the trolley-way 34 is caused, to take place following or simultaneously with transmission of the trolley 38.

If desired, a plurality of apparatuses as above described may be mounted upon the same runways 3 so that cargo may be lifted simultaneously from hatches disposed lengthwise of the ship 1.

This invention has herein been described by reference to one specific illustrative instance of its embodiment and use. It is intended, however, that the protection to be afforded hereby be not unnecessarily limited by said specific instance, the intention being that said protection shall extend to the full limit of the inventive advance disclosed herein as defined by the claims to be hereto appended.

I claim:

1. In a self-elevating and lowering support for an athwartship cargo hoist trolley way for ships the combination comprising a pair of parallel fore and aft runways mounted on the deck of a ship straddling a hatch, a stationary positive traction means associated with and extending lengthwise in juxtaposition to each of said runways, two self-propelled shear leg supports constituting a pair mounted for fore and aft movement on each of said runways, each of said shear leg supports having positive driving means in positive driving engagement with that stationary positive traction

means which is associated with the runway upon which said shear leg support is mounted, a pair of shear legs for each runway, each of said pairs of shear legs being pivotally mounted at the foot ends thereof on respective pairs of shear leg supports, a hoisting trolley supporting girder extending between said shear legs and attached at its opposite ends to said shear legs, and means adapted to cause said shear leg supports to be driven toward and away from one another in pairs to cause elevation and lowering of said girder and adapted to cause said shear leg supports to be driven in a set in unison to impart fore and aft movement to said girder.

2. In a self-elevating and lowering support for an athwartship cargo hoist trolley way for ships the combination comprising a pair of parallel fore and aft runways mounted on the deck of a ship straddling a hatch, a stationary traction chain associated with and extending lengthwise in juxtaposition to each of said runways, two self-propelled shear leg supports constituting a pair mounted for fore and aft movement on each of said runways, each of said shear leg supports having a sprocket in positive driving engagement with that chain which is associated with the run-

way upon which said shear leg support is mounted, a pair of shear legs for each runway, each of said pairs of shear legs being pivotally mounted at the foot ends thereof on respective pairs of shear leg supports, a hoisting trolley supporting girder extending between said shear legs and attached at its opposite ends to said shear legs, and means adapted to cause said shear leg supports to be driven toward and away from one another in pairs to cause elevation and lowering of said girder and adapted to cause said shear leg supports to be driven in a set in unison to impart fore and aft movement to said girder.

NILS PETER ERIK ANDERSEN.
